UNITED STATES PATENT OFFICE.

THEODORE E. WIEDERSHEIM, JR., OF PHILADELPHIA, PENNSYLVANIA.

DESIGN FOR A BOX.

SPECIFICATION forming part of Design No. 24,470, dated July 16, 1895.

Application filed May 23, 1895. Serial No. 550,456. Term of patent 3½ years.

To all whom it may concern:

Be it known that I, THEODORE E. WIEDERSHEIM, Jr., a citizen of the United States, residing in the city and county of Philadelphia, State of Pennsylvania, have invented and produced a new and original Design for a Box, of which the following is a specification, reference being had to the accompanying drawing, forming part thereof.

5 o The leading feature of my design for a box is the body of the form of a chimney and a flap rising from one side thereof of the form of the upper part of a man and forming a continuity of said side.

5 In the drawing, A designates the body of a box, the same simulating the form of a chimney.

B represents a flap of the form of the upper part of a man, the same being an upward continuity of one side of the body of the box 20 and projects above the top thereof. The lower part of said figure is represented on said side.

The body of the box is ornamented with representations of ice and snow. 25

What I claim is—

The design for a box, substantially as described and shown.
